DESIGN FOR A HANDBAG OR SIMILAR ARTICLE

Bernard B. White, New York, N. Y.

Application November 12, 1940, Serial No. 96,500

Term of patent 3½ years

To all whom it may concern:

Be it known that I, Bernard B. White, a citizen of the United States of America, residing in New York city, county of New York, and State of New York, have invented a new, original, and ornamental Design for a Handbag or Similiar Article, of which the following is a specification, reference being had to the accompanying drawing, forming part thereof, wherein:

I claim:

The ornamental design for a handbag or similiar article, substantially as shown.

BERNARD B. WHITE.
